UNITED STATES PATENT OFFICE.

CHARLES W. SMITH, OF NORWALK, OHIO.

DESIGN FOR A CURTAIN-POLE BRACKET.

SPECIFICATION forming part of **Design No. 24,107**, dated **March 12, 1895**.

Application filed February 9, 1895. Serial No. 537,832. Term of patent 7 years.

To all whom it may concern:

Be it known that I, CHARLES W. SMITH, a citizen of the United States, residing at Norwalk, in the county of Huron and State of Ohio, have invented a certain new and useful Design for Curtain-Pole Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation of my curtain pole bracket, and Fig. 2, is a cross section on the line α , α of Fig. 1.

My design has reference to brackets for curtain poles, the special features of the design 20 being an annular pole supporting the portion A, having the central perforation a , the sides of the said annular portion being flat and in parallel planes and having a circumferential bead C, with a convex surface, and a recess 25 D on each side of the said bead. The said annular portion A has contact with the cen-

tral convex bead E, having a recess e , e , at each side, and the outwardly flaring portions F, F, terminating at their greatest diameter in the ridges II, II, from which ridges are the 30 outwardly contracting convex surfaces J and J', the latter of which terminates in a cylindrical portion K which is connected to a series of convex beads m, n, and o, the latter of which is connected to an outwardly flaring 35 semi-spherical portion S with a concaved neck T.

R is an outwardly flaring concaved portion between the contracted portion of the convex surface J and the ridge R', and V is a convex 40 surface contracting outwardly and connected to the globular portion U having a concaved apex terminating in an abrupt cone.

What I claim is—

The design for a curtain pole bracket as 45 herein shown and described.

In testimony whereof I affix my signature in presence of two witnesses.

CHARLES W. SMITH.
